101,784

DESIGN FOR A LIQUID CLEANER

Leonard J. Kurtz, Cleveland, Ohio

Application March 25, 1936, Serial No. 61,781

Term of patent 7 years

To whom it may concern:

Be it known that I, Leonard J. Kurtz, a citizen of the United States, residing at Cleveland, in the county of Cuyahoga and State of Ohio, have invented a new, original, and ornamental Design for a Liquid Cleaner, of which the following is a specification, reference being had to the accompanying drawing, forming part thereof.

Fig. 1 is a perspective view of a liquid cleaner embodying my new design; and

Fig. 2 is a left end elevation thereof.

I claim:

The ornamental design for a beverage stick, as shown.

LEONARD J. KURTZ.

CERTIFICATE OF CORRECTION.

Design No. 101,784.

November 3, 1936.

LEONARD J. KURTZ.

It is hereby certified that error appears in the printed specification of the above numbered patent requiring correction as follows: Second column, line 5, in the claim, for the words "beverage stick" read liquid cleaner; and that the said Letters Patent should be read with this correction therein that the same may conform to the record of the case in the Patent Office.

Signed and sealed this 23rd day of February, A. D. 1937.
